UNITED STATES PATENT OFFICE.

NELSON BECKWITH, JR., OF CAMBRIDGE, MASSACHUSETTS, ASSIGNOR, BY MESNE ASSIGNMENTS, TO CAPITOLA PILLSBURY BECKWITH, OF SAME PLACE.

PACKING-CASE FASTENING.

SPECIFICATION forming part of Letters Patent No. 377,477, dated February 7, 1888.

Application filed March 25, 1887. Serial No. 232,357. (No model.)

To all whom it may concern:

Be it known that I, NELSON BECKWITH, Jr., of Cambridge, in the county of Middlesex and State of Massachusetts, have invented a new and useful Improvement in Packing-Case Fastenings, which will, in connection with the accompanying drawings, be hereinafter fully described, and specifically defined in the appended claims.

10 In said drawings, Figure 1 is a perspective view showing my invention as applied to a packing-case, which latter is shown in part. Fig. 2 is a section taken on line X X, Fig. 1, but showing in perspective the locking-stud, which in Fig. 1 is omitted. Fig. 3 is a perspective view of the clamping-strap as secured to the packing-case. Fig. 4 is a horizontal section taken as on line W W, Fig. 2.

My invention relates to a device for securing in place the covers of packing cases or boxes which are formed with parallel opposite sides or faces and right-angle corners; and it consists in features of novelty hereinafter fully described, and pointed out in the claims.

25 Referring to the drawings, A represents the end of the packing case or box, B the cover, and C a cleat secured to the upper part of end A, both ends of the case being alike, and the height, length, and breadth thereof of any desired dimension. To the end of the case I secure a strap, D, having a lower member, a, secured to end A by the studs g, formed upon strap D, and a screw or nail, e; the oblique angle b, bearing against the lower edge of cleat

35 C; the part c, resting against the outer face of the cleat; angle d, extending across the top edge of the cleat and end, and a lip, f, flush with the inner face of end A and serving to secure the end and cleat together. In the horizontal part d of said strap is formed an elongated opening, h, as is clearly shown in Fig. 3. Upon the cover or top B is secured the metallic cap-plate E by screws m, said plate being formed with a depression, i, in the floor 40 of which is cut an opening, j, of "key-hole" form, while at the front thereof is a depression, k, and transversely thereto, on both sides of opening j, is a depression, l, Fig. 1.

A locking-stud, F, is formed with a cylind-

rical body, q, a bar-like upper head, s, and 50 a similar head, t, the longer line of which is at right angles to the longer line of head s. Said head t of locking-stud F and hole j in cap-plate E have such relation to each other in size and form that by arranging body q 55 obliquely to the plane of cap-plate E the head t may, by entering one of its ends first in the hole, be passed therethrough, and thereafter the locking-stud remains permanently in cap-plate E, whether top B is secured to the 60 case or is removed therefrom. Said head t, when duly arranged, passes freely through hole h in strap D; and to secure the cover in place the locking-stud is so arranged that head s rests in depression k, when head t will readily pass through hole h in strap D, as stated, when, by turning the locking-stud a quarter of a circle, so as to bring the head s to bear in depressions l, the cover will be securely 65 locked to the case and the locking-stud be secured against accidental rotation, as head s is below the level of the cap-plate, the angle or part d of the strap being formed slightly oblique to part c, as indicated by dotted lines in 70 Fig. 2, so that when the locking-stud is duly locked said part d, by its tendency to rise, will hold the locking-stud closely in place. Said cap-plate E is formed with lugs n n, which 75 embrace the edges of strap D to prevent lateral displacement of the cover, while a lug, p, 80 secures the cover from end displacement.

I claim as my invention—

1. The combination of strap D, cap-plate E, and locking-stud F, said strap adapted to be secured to the vertical wall of the case and to 85 overlap the upper edge thereof and provided with an opening, h, to receive the lower head of the locking-stud, the cap-plate being secured to the cover and having an opening, j, to receive said locking-stud, the latter being 90 formed with two heads, each at right angles to the plane of its body q, substantially as specified.

2. The combination, with strap D and locking-stud F, formed as specified, of cap-plate 95 E, formed with a recess, i, to receive one of the heads of said locking-stud, and openings j, through which the locking-stud may be in-

serted, and a floor or bottom on which the head *s* of the locking-stud may bear, substantially as specified.

3. The combination, with strap *D* and locking-stud *F*, of the cap-plate *E*, formed with opening *j* and recess *i* to receive said locking-stud, and with depressions *k* and *l*, formed in

the floor of said recess, to receive head *s* of said locking-stud, substantially as specified.

NELSON BECKWITH, JR.
